US00D364855S

United States Patent [19]

Onoda

[11] Patent Number: Des. 364,855

[45] Date of Patent: **Dec. 5, 1995

[54] DISPLAY APPARATUS FOR ELECTRONIC COMPUTERS

842277 7/1992 Japan .
863348 3/1993 Japan .
867462 4/1993 Japan .

[75] Inventor: Hiroshi Onoda, Tokyo, Japan

Primary Examiner—Freda Nunn
Attorney, Agent, or Firm—Banner & Allegretti, Ltd.

[73] Assignee: Kabushiki Kaisha Toshiba, Japan

[57] **CLAIM**

[**] Term: 14 Years

The ornamental design for a display apparatus for electronic computers, as shown and described.

[21] Appl. No.: 29,069

DESCRIPTION

[22] Filed: Sep. 28, 1994

FIG. 1 is a top, front and right side perspective view of a display apparatus for electronic computers showing my new design according to a first embodiment;

[30] Foreign Application Priority Data

FIG. 2 is a front elevational view thereof;

Mar. 29, 1994 [JP] Japan 6-8233

FIG. 3 is a left side elevational view thereof;

Mar. 29, 1994 [JP] Japan 6-8234

FIG. 4 is a right side elevational view thereof;

[52] U.S. Cl. D14/113

FIG. 5 is a rear elevational view thereof;

[58] Field of Search D14/100, 101,

FIG. 6 is a top plan view thereof;

D14/105, 106, 113, 124-129, 345/104,

FIG. 7 is a bottom plan view thereof;

133, 156, 168, 87, 173, 901-905; 358/249,

FIG. 8 is a top, front and right side perspective view of a display apparatus for electronic computers showing my new design according to a second embodiment;

254, 255, 248/917-924

FIG. 9 is a front elevational view thereof;

[56] References Cited

FIG. 10 is a right side elevational view thereof; and,

U.S. PATENT DOCUMENTS

FIG. 11 is a top plan view thereof.

D. 344,933 3/1994 Wiseman et al. D14/113

The rear elevational, left side elevational, and bottom plan views of the second embodiment are the same as those of the first embodiment shown in FIGS. 3, 5 and 7 respectively.
